UNITED STATES PATENT OFFICE.

FREDERICK CLAYMAN, OF RUSH, NEW YORK.

DITCHING-MACHINE.

No. 923,141.

Specification of Letters Patent.

Patented June 1, 1909.

Application filed July 13, 1908. Serial No. 443,294.

To all whom it may concern:

Be it known that I, FREDERICK CLAYMAN, a citizen of the United States, residing at Rush, in the county of Monroe and State of New York, have invented a new and useful 5 Ditching-Machine, of which the following is a specification.

This invention relates to ditching machines, and especially to machines of that 10 general type employed for digging shallow trenches for the reception of drain tiles and the like.

The principal object of the invention is to 15 provide a machine of simple construction which may be operated by horse power or a traction engine, and in which the earth may be gradually sliced away and deposited at a point to one side of the trench.

A further object of the invention is to provide 20 a machine of this type in which the parts may be readily adjusted for the purpose of making a cut at any desired depth, and in which the cutting blade or knife may be angularly adjusted in accordance with 25 the depth of cut.

A still further object of the invention is to 30 simplify and improve the actuating and controlling mechanism so as to place the same within reach of the driver or other operator.

With these and other objects in view, as 35 will more fully hereinafter appear, the invention consists in certain novel features of construction and arrangement of parts, hereinafter fully described, illustrated in the accompanying drawings, and particularly pointed out in the appended claims, it being understood that various changes in the form, proportions, size and minor details of the structure may be made without departing 40 from the spirit or sacrificing any of the advantages of the invention.

In the accompanying drawings:—Figure 1 is a side elevation of a ditching machine constructed in accordance with the invention. 45 Fig. 2 is a similar view looking from the opposite side of the machine. Fig. 3 is a plan view of the machine. Fig. 4 is a transverse sectional view of the machine on an enlarged scale, the view being taken on the plane indicated by the line 4—4 of Fig. 1. Fig. 5 is a detail transverse section on the line 5—5 in Fig. 1. Fig. 6 is a detail longitudinal section on the line 6—6 of Fig. 5. Fig. 7 is a side elevation illustrating on an enlarged 50 scale one of the hangers for the support of the uppermost conveyer shaft. Fig. 8 is a

detail sectional view of the same on the line 8—8 of Fig. 7.

Similar numerals of reference are employed to indicate corresponding parts throughout 60 the several figures of the drawings.

The principal portion of the machine is supported on a shaft or axle 10 at the opposite ends of which are mounted loose wheels 11, the wheels being connected to the shaft 65 11, by a pawl and ratchet mechanism 12, so arranged that the shaft 10 will be rotated when the machine is traveling in a forward direction, but will be idle if the machine is backed.

Mounted loosely on the shaft are collars 15 70 and 16 from which extend a plurality of struts or braces 17 that serve as supports for a long trough 18 that is formed of sheet metal or other material. This trough is arranged for the reception of the upper run of 75 a conveyer belt 20 by which the dirt is carried from the cutting blade 21 to the top of the trough, and is discharged through a laterally directed chute 22, the excavated material falling to the ground at one side of the 80 ditch in convenient position for refilling.

The cutting blade 21 is provided at each side with a vertically extended web 24 and near the forward ends of the web are openings for the passage of pivot bolts 25 that extend through openings formed in the side-walls of the trough. Near the rear end of each of the webs is an arcuate series of openings 26 for the passage of bolts 27, the construction being such as to permit proper adjustment of the angle of the cutting blade in 85 accordance with the depth of the excavation. 90

Immediately to the rear of the cutting blade are two vertically disposed plates 29 secured to the outer sides of the trough and 95 provided with vertical slots 30 as shown by dotted lines in Fig. 6. These slots are arranged for the passage of the end portions of a shaft 31 which carries a grooved roller 32, the grooves of the roller serving to receive 100 the link belts 33 of the conveyer, and the sheet metal or other flights 34 of the conveyer are riveted or otherwise secured to said belt. The opposite ends of the shaft 31 are mounted in bearings formed in vertically 105 slidable blocks 37 at the upper portions of which are laterally projecting ears in which are swiveled the lower ends of screws 38. These screws pass through threaded openings formed in brackets 39 that are secured 110 to the side walls of the trough, so that the roller 32 may be vertically adjusted in ac-

cordance with the position of the cutting blade, it being desirable to keep the flights of the conveyer close to the rear edge of the blade, so as to carry off all of the excavated material.

Mounted on the side walls of the upper or discharge end of the trough are channeled plates or blocks 40, each provided with a longitudinal slot 41 for the passage of headed bolts 42 by which the plate is held from outward movement, while the upper and lower flanges of the plate bind against the upper and lower edges of the side wall of the trough, and thus prevent angular displacement. The plate is provided with an outwardly projecting flange 43 to which is swiveled the inner end of a screw 44, that extends through a threaded opening formed in a bracket 45, and by turning the screw, the plate may be adjusted in the direction of the length of the trough. Depending from each plate is a hanger 47, and the two hangers are provided with bearings for the reception of a transversely disposed shaft 48 that carries two sprocket wheels 49 over which the link belts of the conveyer pass. One end of the shaft extends some distance beyond the side of the trough, and carries a sprocket wheel 50, and this wheel is connected by a belt 51 to a sprocket wheel 52 on a transversely disposed shaft 53 extending under the trough. The shaft 53 carries a pinion 54 which intermeshes with a gear 55 on the main shaft or axle 10. The hub of the gear 55 is provided with a clutch pinion that is arranged to be engaged by a clutch collar 58 that is feathered on the shaft 10. The collar has an annular groove that receives the forked end of an operating arm 60 that is pivotally connected to a lever 61 that is arranged within convenient reach of the driver's seat 62. Pivoted to the lever 61 is a locking lever 63 that is provided at its lower end with an outwardly extending arm 64 having a pair of notches 65, either of which may be engaged with a pin 66 carried by a loose collar 67 on the axle, so that the clutching mechanism may be locked in operative or inoperative position. The conveyer may be adjusted in order to maintain it as taut as desired, and the lower run of the conveyer is supported at intervals by idler rollers 68 that are carried by hangers depending from the side of the trough. The forward portion of the lower run of the conveyer is protected by guard plates 70 from contact with the side walls of the ditch being excavated. Secured to the forward portion of the side walls of the trough are outwardly and forwardly curved arms 72 which are reinforced by braces 73. These arms are connected to the rear end of a tongue 74 by means of a pivot bolt 75, and any suitable traction means may be connected to the tongue, the device being operable by horse

power, a traction engine or other draft device.

Pivotedly mounted on the bolt 75 is a bell crank lever 81, and the forward arm of this lever carries an axle 79 on which is mounted a wheel 80 that runs on the surface of the ground in advance of the blade. The rear arm of the bell crank lever is connected by a link 82 to the forward end of a lever 78 that is mounted on a pin or stud 83 carried by a bracket 84. The link 82 and the lever 78 are both provided with a plurality of openings for the passage of the pivot bolts which serve as connections between the link, the bell crank lever and the lever 82, so that these connections may be adjusted in accordance with circumstances. The lever 78 extends rearwardly, preferably to a point within reach of the driver's seat, and may be moved up or down for the purpose of adjusting the position of the wheel 80 and thus increasing or decreasing the depth of cut. The lever may then be locked in position by a suitable locking device 86 of any desired construction. As a further means of adjustment, the rear end of the tongue 74 is provided with an approximately U-shaped arm 87, that is connected to the forward end of a chain 88. This chain extends over a guiding sheave 89 which is mounted on the stud 83, and the rear end of the chain is secured to a winding drum 90 that is mounted in bearings in small brackets 91 at the sides of the trough, and the winding drum having a suitable operating crank which may be turned for the purpose of winding up the chain and thus adjusting the forward end of the machine.

With a machine of this type, trenches of considerable depth and width may be rapidly excavated and the excavated material deposited at one side of the ditch in convenient position for refilling.

What is claimed is:—

1. In an excavating machine, a pair of supporting wheels, an axle connecting the same, an angularly adjustable trough mounted on said axle, an endless conveyer extending through the trough, a driving connection between the axle and the conveyer, an angularly adjustable cutting blade at the lower end of the trough, and means for locking the cutting blade in adjusted position.

2. In a ditching machine, a pair of supporting wheels, an axle connecting the same, an inclined trough, collars mounted loosely on the axle, a plurality of braces and struts connecting the collars to the trough, an endless conveyer, the upper run of which extends through the trough, a driving connection between the conveyer and axle, means for vertically adjusting the forward end of the conveyer, and a cutting blade at the lower end of the trough.

3. In a ditching machine, a pair of supporting wheels, an axle connecting the

- same, an inclined trough, collars mounted on the axle, a plurality of braces and struts extending from the collars to the trough, means for adjusting the angle of the trough, 5 to the line of cut, a conveyer extending through the trough, means for vertically adjusting the forward end of the conveyer, and a cutting blade at the lower end of the trough.
- 10 4. In a ditching machine, a pair of supporting wheels, an axle connecting the same, an inclined trough pivotally mounted on the axle, shafts journaled near the upper and lower ends of the trough, sprocket wheels 15 on said shafts, an endless conveyer having link belts mounted on the sprocket wheels, a counter-shaft connected to the uppermost of said belt carrying shafts, a pinion on said counter-shaft, a gear mounted loosely on the axle, and a clutching connection between 20 the gear and the axle.
5. In a ditching machine, a pair of supporting wheels, an axle connecting the wheels, a trough pivotally mounted on the 25 axle, an endless conveyer arranged to run in the trough, a cutting blade at the lower end of the trough, a carrying wheel for supporting the forward end of the machine, and means for adjusting said carrying wheel to 30 raise or lower the forward end of the trough.
6. In a ditching machine, a pair of supporting wheels, an axle connecting the same, a trough pivoted on the axle, an endless conveyer arranged to run in the trough, a cutting 35 blade at the lower end of the trough, a frame extended forward from the trough,
- a draft tongue pivoted to said frame, a bell crank lever pivoted at the juncture of the frame and tongue, a supporting wheel carried by one arm of the lever, and an adjusting means connected to the opposite arm of 40 said lever.
7. In a ditching machine, a pair of supporting wheels, an axle connecting the same, a trough pivotally mounted on the axle, an 45 endless conveyer in the trough, a cutting blade at the lower end of the trough, a frame extended forward of the trough, an adjustable supporting wheel pivoted to the frame, a draft tongue connected to said frame and 50 provided with a rearward extending arm, a winding drum mounted on the trough, a chain extending from the winding trough to the arm, and means for guiding said chain.
8. In a machine of the class described, a 55 trough having side webs, a cutting blade also provided with side webs, pivot bolts extending through the forward portions of the webs, and on which the blade is angularly adjustable, an arcuate series of openings 60 extending through each of the webs of the blade, and securing bolts arranged to extend through said openings and lock the blade in adjusted position.
- In testimony that I claim the foregoing 65 as my own, I have hereto affixed my signature in the presence of two witnesses.

FREDERICK CLAYMAN.
